CENTRIFUGAL FAN

James R. Davis, La Crosse, Wis., assignor to The Trane Company, La Crosse, Wis.

Application June 14, 1954, Serial No. 436,336

5 Claims. (Cl. 230—127)

This invention relates to centrifugal fans wherein an impeller is rotatably mounted in a scroll shaped housing for drawing air into the fan axially thereof and discharging the air radially from the impeller into the housing from which it flows through a discharge opening.

In order to provide a relatively large discharge opening, the sides of the fan housing are disposed at some distance from the sides of the impeller and there is a tendency for the air to rotate continuously in the housing, particularly about the inlet throat of the housing and the inlet side plate of the impeller. This rotation of air in the housing produces losses which reduce the efficiency of the fan.

It is, therefore, an object of this invention to provide a first cut-off member extending across said housing and a second cut-off member extending from the side of the housing to a point adjacent to the outer periphery of the side plate of the impeller.

It is a further object of the invention to provide a cut-off which will reduce recirculation of air about the inlet throat of the housing and the inlet side plate of the impeller thus increasing the efficiency of the fan.

It is still another object of the invention to provide a shroud in the housing about the inlet thereof to reduce the recirculation of air in the housing.

Further objects and advantages of this invention will become apparent as the specification proceeds to describe the invention with reference to the accompanying drawings in which:

Figure 1 is a vertical cross-sectional view through a centrifugal fan incorporating the features of this invention.

Figure 2 is an end elevational view of the fan shown in Figure 1 as viewed from the right hand end thereof.

Figure 3 is an end elevational view of a double inlet fan incorporating the features of this invention.

Figure 4 is a perspective view of the cut-off assembly of the fan of Figure 3.

The invention has been illustrated as applied to a centrifugal fan having an impeller positioned in a relatively large housing scroll to permit expansion of the air after passing through the impeller to obtain a low velocity discharge of air and the accompanying quiet operation.

The fan of this invention consists of a housing 10 having parallel side walls 12 and 14 which are fastened to opposite edges of a scroll 16. The housing has a substantially rectangular discharge opening 18. The discharge opening 18 is spaced from and in a plane substantially parallel with a plane tangent to the periphery of the impeller 20. Two sides of the discharge opening are substantially at the housing sides 12 and 14. A third side of the discharge opening is substantially at the scroll shaped wall 16. The fourth side of the discharge opening 18 is substantially in a plane through the axis of rotation of the impeller 20 and normal to the plane of the discharge opening 18.

An impeller 20 is positioned within the scroll housing 10 and is mounted on a drive shaft 22 which is rotatably supported in a bearing 24 positioned externally of the scroll housing 10.

The impeller 20 has a plurality of blades 26 positioned about its periphery. The blades 26 extend between and are secured at their ends to the inlet side plate 28 and the back side plate 30 of the impeller in any suitable manner as by welding or riveting.

The inlet side plate 28 of the impeller 20 has an inlet

2

opening 32 which forms the inlet plane of the impeller. An inlet throat 34 is secured to the wall 12 in any suitable manner as by welding, riveting, or bolting, and has the end 36 thereof extending within the inlet plane 32 of the impeller 20 to conduct air through the inlet throat and thence directly into the interior of the impeller 20.

The side plate 12 of the housing 10 is formed inwardly to form a shroud 38 surrounding inlet 34.

5 10 A main cut-off member 40 extends across the discharge opening 18 and is secured at 42 to the scroll 16 in any suitable manner as by resistance welding. In cross section the main cut-off member 40 is substantially in the form of an inverted U.

15 15 A secondary cut-off member 44 is secured to the main cut-off member 40 at 46 in any suitable manner as by resistance welding. The secondary cut-off member 44 extends from the side 12 of the housing to a point short of the plane of the edge of the large end of the inlet side plate 28 of the impeller 20.

20 It has been found that prior art fans having only a cut-off similar to the main cut-off 40 have permitted the air or gas to circulate continuously in the housing particularly about the inlet throat and about the inlet side

25 25 plate of the impeller. This recirculation of air in the housing reduces the efficiency of the fan. In order to reduce this recirculation and increase the efficiency of the fan, applicant has provided the shroud 38 and the secondary cut-off member 44. The secondary cut-off

30 30 member 44 provides efficient flow in the discharge area of the housing and prevents recirculation with substantial clearances between the impeller and stationary parts thus avoiding frictional losses which would otherwise result.

35 35 A fastening clip 50 is secured to the cut-off member 40 and to the housing side plate 12 in any suitable manner as by resistance welding. Strut 48 is also secured to cut-off members 40 and 44 at 52 and 54 respectively, in any suitable manner as by resistance welding. A strut 56 is secured to members 40 and 44 at 58 and 60 respectively in any suitable manner as by resistance welding.

40 40 The extremity of the second cut-off member, as shown in the drawings, is rounded and is provided with portions 61 and 62, which are parallel to the axis of rotation of the impeller.

45 45 In Figure 3 there is illustrated the use of the air cut-off members 40 and 44 and the shroud 38 as applied to a double inlet centrifugal fan. The arrangement of the elements of construction of the double width fan 10' is similar to that of the single width fan 10, however, since there are two inlets there are two shrouds 38' and two secondary cut-offs 44'. A single main cut-off 40' extends entirely across the housing. The shroud members 38' and secondary cut-off members 44' function in the same manner as described in connection with the operation of the apparatus illustrated in Figure 2.

50 50 The extremity of the second cut-off member, as shown in the drawings, is rounded and is provided with portions 61' and 62', which are parallel to the axis of rotation of the impeller.

55 55 While the apparatus disclosed and described herein constitutes a preferred form of the invention, yet it will be understood that the apparatus is capable of alteration without departing from the spirit of the invention, and that all modifications that fall within the scope of the appended claims are intended to be included herein.

Having thus fully described my invention, what I claim as new and desire to secure by Letters Patent is:

1. In a centrifugal fan, a housing of scroll form having spaced substantially parallel sides and a scroll shaped wall, an inlet throat extending within said housing from one side thereof, an impeller of the centrifugal type having

70 70

flow passages therein and having said flow passages terminating in a peripheral air discharge surface, means rotatably mounting said impeller in said housing for drawing air through the inlet throat into said impeller and discharging the same from the fan housing, a substantially rectangular discharge opening in said housing, said opening being spaced from and in a plane substantially parallel with a plane tangent to the periphery of said impeller, two sides of said discharge opening being substantially at the housing sides, a third side of said discharge opening being substantially at the scroll shaped wall, a fourth side of said discharge opening being substantially in a plane through the axis of rotation of the impeller and normal to the plane of said discharge opening, a first air cut-off member secured to said housing at said fourth side of said discharge opening and extending into said discharge opening, said first air cut-off member being spaced from and extending substantially across said peripheral air discharge surface of said impeller, and a second air cut-off member secured to said housing and extending from the inlet side of said housing substantially to said peripheral air discharge surface of said impeller, said second air cut-off member extending into the discharge opening from said fourth side of said discharge opening a greater distance than said first air cut-off member, said impeller having a side wall axially converging toward the said inlet and providing a passageway in the said side wall which registers with said inlet, the said second cut-off member axially overlapping the said converging side wall.

2. In a centrifugal fan, a housing of scroll form having spaced substantially parallel sides and a scroll shaped wall, an inlet throat extending within said housing from one side thereof, an impeller of the centrifugal type having flow passages formed by elements having outer edges therein, said flow passages terminating in a peripheral air discharge surface, means rotatably mounting said impeller in said housing for drawing air through the inlet throat into said impeller and discharging the same from the fan housing, a substantially rectangular discharge opening in said housing, said opening being spaced from and in a plane substantially parallel with a plane tangent to the periphery of said impeller, two sides of said discharge opening being substantially at the housing sides, a third side of said discharge opening being substantially at the scroll shaped wall, a fourth side of said discharge opening being substantially in a plane through the axis of rotation of the impeller and normal to the plane of said discharge opening, a first air cut-off member secured to said housing at said fourth side of said discharge opening and extending into said discharge opening, said first air cut-off member being spaced from and extending substantially across said peripheral air discharge surface of said impeller, and a second air cut-off member secured to said housing and extending from the inlet side of said housing substantially to said peripheral air discharge surface of said impeller, said second air cut-off member extending into the discharge opening from said fourth side of said discharge opening a greater distance than said first air cut-off member, said impeller having a side wall axially converging toward the said inlet and providing a passageway in the said side wall which registers with said inlet, the said second cut-off member axially overlapping the said converging side wall, the inner extremity of said second air cut-off member being rounded and having portions substantially parallel to the axis of rotation of said impeller, the radially innermost portion with respect to the axis of said impeller being substantially in line with said outer edges of said elements of the peripheral air discharge surface of said impeller.

3. In a centrifugal fan, a housing of scroll form having spaced substantially parallel sides and a scroll shaped wall, an inlet throat extending within said housing from one side thereof, an impeller of the centrifugal type having an inlet side plate with an air receiving opening in

communication with said inlet throat, said impeller having flow passages therein and having said flow passages terminating in a peripheral air discharge surface, means rotatably mounting said impeller in said housing for drawing air through said inlet throat into said impeller and discharging the same from the fan housing, a substantially rectangular discharge opening in said housing of substantially the same width as said housing, and an annular shroud member extending axially inwardly toward said impeller, said shroud member being secured to said one side of said housing and surrounding said inlet throat, said annular shroud member being spaced from said inlet throat to reduce the recirculation of air around said inlet throat.

15. 4. In a centrifugal fan, a housing of scroll form having spaced substantially parallel sides and a scroll shaped wall, an inlet throat extending within said housing from each side thereof, an impeller of the centrifugal type having inlet side plates, each of said side plates having an air receiving opening in communication with one of said inlet throats, said impeller having flow passages therein and having said flow passages terminating in a peripheral air discharge surface, means rotatably mounting said impeller in said housing for drawing air through the inlet 20 throat into said impeller and discharging the same from said housing, a substantially rectangular discharge opening in said housing, said opening being spaced from and in a plane substantially parallel with a plane tangent to the periphery of said impeller, two of the sides of said discharge opening being substantially at the housing sides, a third side of said discharge opening being substantially at the scroll shaped wall, a fourth side of said discharge opening being substantially in a plane through the axis of 25 rotation of the impeller and normal to the plane of said discharge opening, a first air cut-off member secured to said housing at said fourth side of said discharge opening and extending substantially across said peripheral air discharge surface of said impeller, additional air cut-off members secured to said housing and extending from the sides of said housing substantially to said peripheral air discharge surface of said impeller, said additional air cut-off members extending into said discharge opening from said fourth side of 30 said discharge opening a greater distance than said first air cut-off member, said impeller having a side wall axially converging toward the said inlet and providing a passageway in the said side wall which registers with said inlet, the said second cut-off member axially overlapping the said converging side wall.

5. In a centrifugal fan, a housing having spaced substantially parallel sides and a scroll shaped wall, an inlet throat extending within said housing from each side thereof, an impeller of the centrifugal type having inlet side plates, each of said side plates having an air receiving opening in communication with one of said inlet throats, said impeller having flow passages therein and having said flow passages terminating in a peripheral air discharge surface, a substantially rectangular discharge opening in said housing of substantially the same width as said housing, and annular shroud members extending axially inwardly toward said impeller, said shroud members being secured to the sides of said housing and surrounding said inlet throats, said annular shroud members being spaced from said inlet throats to reduce the recirculation of air around said inlet throats.
